UNITED STATES PATENT OFFICE.

WILBER E. McELDOWNEY, OF DENVER, COLORADO, ASSIGNOR TO THE MILLER ELECTRIC SWITCH COMPANY, A CORPORATION OF COLORADO.

WATERPROOF SWITCH-JOINT.

1,162,793.

Specification of Letters Patent.

Patented Dec. 7, 1915.

Application filed May 27, 1913. Serial No. 770,205.

To all whom it may concern:

Be it known that I, WILBER E. McELDOWNEY, a citizen of the United States, residing at Denver, Colorado, have invented certain new and useful Improvements in Waterproof Switch-Joints, of which the following is a specification.

My invention relates to improvements in water proof switch joints, and the objects of my improvements are to provide a joint in a switch throwing device that will prevent moisture passing into the mechanism or in the solenoidal containing compartment of the switch throwing device; to provide a water proof joint that will attain the objects without the use of liquids in the joint and to provide a water proof joint that may be adjusted from time to time and at the same time give support to the throwing arm or lever of a switch throwing device. I attain these objects by the mechanisms illustrated in the accompanying drawings, in which:

Figure 1 is a plan view in broken section showing the relative position of my device; Fig. 2 is a perpendicular cross sectional view of the device; Fig. 3 is a cross sectional view of a solenoid switch throwing mechanism; Fig. 4 is a plan view of a metal washer; Fig. 5 is a plan view of a fiber washer; Fig. 6 is a cross sectional view of Fig. 5 at line C—D; and Fig. 7 is a cross sectional view of Fig. 4 at line A—B.

Similar numerals refer to similar parts throughout the several drawings.

In a box 1, adapted to be placed beneath the surface of the ground, is a solenoid 2, connected by lever 3 with the switch throwing element 4, to which switch throwing element 4 is attached a shaft 6 turnable in the bracket 5. The inner lid 7 of the box 1 is provided with certain forms surrounding the shaft 6, described as follows:—A stuffing box 8 depends from the lid 7, having an interior space 9 larger than the shaft 6, except at the bottom of the box 8, where the edges close around the shaft 6. On the upper side of the inner lid 7 is an upwardly extending annular boss 13. The shaft 50 throwing lever is made in two parts 14 and 15, for convenience of construction, and for purposes of invention they may be considered as integral. This switch throwing lever is attached to the shaft 6 by bolt means 55 16 and the two parts 14 and 15 are joined

by bolts 19. It may be added that by making the shaft arm in the two parts there may be placed between them and extending over the joint made between the upper part 15 and the shaft 6 water-proof material to prevent the entrance of any moisture at the top of shaft 6. At the outer end of the switch throwing lever the bar 17 is attached to be connected with the switch tongue. The interior 9 of the stuffing box surrounding the shaft 6 is filled the required distance with alternating washers consisting of metal washers 10 and fiber washers or pliable washers 11. The metal washer 10 is provided with a shoulder 10^a so that the fiber washer 11, is constructed so that the inner portion of the washer 11 will turn up into the space made by the shoulder 10^a, as shown in Fig. 2. At the top of the box on the interior 9 thereof, a gland nut 12 is provided, screw-threaded, in the lid 7 and provided with means for the application of a spanner wrench for adjustment. The under side of the switch throwing lever 14 is provided with a cup 13^a adapted to receive the boss 13, with the sides 18 and 18^a extending down to and closely fitting over the cover 7 and the gland nut 12.

It will be seen that when the device is assembled, the fiber washers 11, being made the requisite size, are forced upwardly and against the sides of the shaft 6 and that the amount of pressure may be furnished by the adjustment of the gland nut 12, as may be required, and thereby take up any slack that should occur in the fiber washer 11. It is to be noticed, also, that by this construction the throwing lever, herein described as composed of parts 14 and 15, is sustained by the annular boss 13 so that the strain is not wholly upon the shaft 6, and its bearings, but is borne in part by the annular boss 13 and its bearings.

I am aware that waterproof joints, and especially mercury wells, have been in use, but in my device I am not relying upon the use of any of the parts in connection with mercury, or waterproof liquid.

I claim:

In a waterproof switch joint of the character described with which is provided a box containing a solenoid and a switch throwing mechanism; the combination of a shaft attached at one end to a switch throwing mechanism and at the other end to a lever

adapted to be connected with a switch tongue; and a stuffing box integral with and depending from the cover of the said containing box adapted to surround said shaft and to contain moisture proof material; a superimposed annular boss integral with said cover on the upper side thereof, extending above said cover; a gland nut adapt-

ed to fit on the interior of said stuffing box and an annular cup on the underside of said lever adapted to engage said annular boss, all substantially as described.

WILBER E. McELDOWNNEY.
